UNITED STATES PATENT OFFICE

129,941

DESIGN FOR AN ILLUMINABLE ADVERTISING SIGN

Lewis E. Peters, Chicago, Ill., assignor to Raymond M. Price, Chicago, Ill., doing business under the name of Raymond M. Price and Associates

Application June 17, 1941, Serial No. 101,487

Term of patent 3½ years

To all whom it may concern:

Be it known that I, Lewis E. Peters, a citizen of the United States of America, residing at Chicago, in the county of Cook and State of Illinois, have invented a new, original, and ornamental Design for an Illuminable Advertising Sign, of which the following is a specification, reference being had to the accompanying drawing, forming a part thereof.

I claim:

The ornamental design for an illuminable advertising sign, substantially as shown.

LEWIS E. PETERS.
